(57) **CLAIM**

I claim the ornamental design for a charcoal briquet, as shown and described.

DESCRIPTION

FIG. 1 is a perspective view of a charcoal briquet showing my new design;

FIG. 2 is an end elevational view thereof, the elevational view of the opposing end being identical thereto;

FIG. 3 is a side elevational view thereof, the elevational view of the opposing side being identical thereto; and,

FIG. 4 is a top plan view thereof, the bottom plan view being identical thereto.

1 Claim, 2 Drawing Sheets

FIG.1.

FIG.2.

FIG.3.

FIG.4.
